ATTORNEY.

UNITED STATES PATENT OFFICE.

HUGH McCONNELL, OF CLEVELAND, OHIO.

OIL-STOVE TOP.

SPECIFICATION forming part of Letters Patent No. 245,302, dated August 9, 1881.

Application filed May 17, 1881. (No model.)

To all whom it may concern:

Be it known that I, HUGH McCONNELL, of Cleveland, county of Cuyahoga, State of Ohio, have invented a new and useful Improvement 5 in Oil-Stove Tops; and I declare the following to be a full, clear, and exact description of the invention, such as will enable others skilled in the art to which it pertains to make and use it, reference being had to the accompanying 10 drawings, which form a part of this specification.

My invention consists in the combinations of devices and appliances hereinafter set forth, and pointed out in the claims.

15 In the drawings, Figure 1 is a perspective view of the stove-top, showing one of the end pieces detached and slightly removed from the adjacent section. Fig. 2 is a longitudinal central section through the top of the stove. Fig. 20 3 is a section along $y y$.

The object of the invention is to produce an oil-stove top in which the heat of the lamp will be prevented from wasteful outside diffusion and directed against the cooking utensils, and 25 also to facilitate repair of the stove-top.

It consists in a novel construction and means of connecting separable central and end sections of an oil-stove top, as will be hereinafter fully described, and specifically pointed out in 30 the claims.

In the drawings, Fig. 2, A is a lamp of any ordinary construction.

The stove-top is composed of a central section, B, two removable end sections, B', and 35 semicircular tin shields B². The ends of the central section each have a central lug, b', so that with a bolt, b⁶, and nut b⁷, as shown in Fig. 2, it may be secured to the end sections, as shown. The rim of each of the end sections projects over the margins of the top plate of the central section and into recesses formed in the top plate, as shown at b⁵, Fig. 1. There is also cast solid with this end section an elevated open scroll-work, flat upon its upper surface, to form a flat rest for cooking utensils, and which obviates the objection before named to the use of points or pins. The rest, being elevated, leaves a space between the bottom of the cooking utensil and the top of the stove,

for the heated air to escape therefrom. To 50 this scroll-work are cast legs b⁴, which extend down to and rest upon the bottom of the central section, as shown in Fig. 2. These legs, with the joints b³, and the bolt at b', make a stiff structure, which will sustain any usual weight. 55 The tin shield B² has an upturned rim, b², which closes the space beneath the end piece, B', and directs all the heat up against the cooking-utensil.

It is frequently the case, in shipping and 60 handling, and even in using such stoves, that the light end portions of the castings are broken; but should one of these removable end pieces be thus broken it alone can be renewed at very slight expense.

The central section, B, is composed of an upper plate and a lower plate, the latter having upright sides so constructed that when the two are placed together they constitute a longitudinal flue.

What I claim is—

1. An oil-stove top composed of a central section, B, having the top and bottom plates separated by an intervening space, the top plate being recessed at the ends, and two removable-attached end sections provided with open-work utensil-supports arranged to extend into said recesses, and having legs resting upon the bottom plate, substantially as described.

2. An oil-stove top with a removable end piece having cast solid therewith an elevated open scroll-work for supporting a cooking-utensil, and legs beneath for resting upon the lower plate of the central section, substantially as described.

3. A stove-top consisting of a central section composed of an upper and lower plate and removable end pieces, in connection with joints b³ and bolts at b', the construction being such that the parts are all secured together by the bolts at b' alone, substantially as described.

In testimony whereof I sign this specification in the presence of two witnesses.

HUGH McCONNELL.
